UNITED STATES PATENT OFFICE.

CHARLES H. TUCKER, OF ST. LOUIS, MISSOURI.

DESIGN FOR A LEAD-PENCIL.

SPECIFICATION forming part of Design No. 31,072, dated June 27, 1899.

Application filed May 27, 1899. Serial No. 718,587. Term of patent 7 years.

To all whom it may concern:

Be it known that I, CHARLES H. TUCKER, a citizen of the United States, residing at St. Louis, in the State of Missouri, have invented and produced a new and original Design for Lead - Pencils, of which the following is a specification, reference being had to the accompanying drawing, forming part thereof.

As shown in accompanying drawing, the leading feature of my design consists of a series of spirally-formed ribs *a*, forming small spirally - arranged intermediate grooves *b*. The series of ribs and grooves are divided at certain intervals by other grooves *c* larger in width and of greater depth. The ribs and grooves are inclined to the left and run parallel with each other and also spirally about

the length of the sheath of the pencil. One series of the ribs and grooves is made of a contrasting color.

The design above described and represented in the annexed drawing is ornamental in appearance and presents a pleasing effect to the eye.

Having described my invention, what I claim as new, and desire to secure by Letters Patent, is—

The design for a lead - pencil, as herein shown and described.

CHARLES H. TUCKER.
